CLAIM

We claim the ornamental design for a saw blade, as shown and described.

DESCRIPTION

FIG. 1 is a perspective view of a saw blade embodying the invention.

FIG. 2 is a side view of the saw blade of FIG. 1; and, FIG. 3 is an enlarged view of a portion of the saw blade of FIG. 1.

The evenly spaced broken lines are for the purpose of showing portions of the saw blade that form no part of the claimed design. The long and short broken lines that define the bounds of the claimed design form no part thereof.
